UNITED STATES PATENT OFFICE.

JOHN C. SCHAFER, OF TIFFIN, OHIO, ASSIGNOR TO SCHAFER ENGINEERING & EQUIPMENT CO., OF PITTSBURGH, PENNSYLVANIA, A CORPORATION OF PENN-SYLVANIA.

FEEDER.

1,419,946.

Specification of Letters Patent. Patented June 20, 1922.

Application filed January 21, 1918. Serial No. 213,112.

To all whom it may concern:

Be it known that I, JOHN C. SCHAFER, a citizen of the United States of America, residing at Tiffin, Seneca County, Ohio, have 5 invented a new and useful Feeder, of which the following is a specification.

This invention relates to apparatus for regulating the flow of material.

This invention has utility when incorporated with material supply and delivery mechanisms.

Referring to the drawings:—

Fig. 1 is a side elevation, with parts broken away of an embodiment of the invention;

Fig. 2 is a wiring diagram of the electric control connections;

Fig. 3 is a detail in side elevation, with cover plate removed, of the control switch;

Fig. 4 is a detail, with parts broken away, of the control switch shifted to the opposite position from the showing of Fig. 3;

Fig. 5 is a section on the line V—V Fig. 1, looking in the direction of the arrow; and

Fig. 6 is a side elevation of the supply way of the hopper or chute, with parts broken away to show the relation of the parts during material flow.

The service or electric supply may be 30 through alternating current three-phase lines 1, 2, 3, respectively connected by lines 3', 4, 5, to terminals so that by the throwing of switch 6 current may be supplied to the lines 7, 8, 9. The line 7 extends to the 35 terminal 10, adjacent the insulated rotatable disk 12 mounted on the shaft 13 carrying the contact plate 14. This contact plate 14 may, when shifted to the position opposite the showing in Fig. 4, close the circuit from the terminal 10 to the terminal 15, for flow 40 through the line 16 to the three-phase motor 17. The line 8 extends directly to this motor. The line 9 extends to the terminal 18 which in the position of the parts of the 45 switch in Fig. 3 coacts with the contact 19 of the insulated disk 20 on the shaft 13 for closing circuit through the terminal 21 and line 22 to the motor 17, thereby closing circuit for the three phases to this motor 17 50 having the drive shaft 23 carrying the pinion 24, actuating the speed reducing gear 25 on the shaft 26 carrying the pulley 27 of a conveyor belt 28 extending about the idle pulley 29 on the shaft 30 carried by bear-

ings 31 mounted in the frame 32. The shaft 55 26 is mounted in bearings 33 also carried by the frame 32. Mounted on this frame 32 is the supplemental frame 34 carrying the rollers 35 for anti-frictionally positioning the conveyor belt 28 below the hopper chute 60 or supply way 36 mounted on the frame 32 by the supplementary frame 37, 38, 39.

The upper slack reach of the conveyor belt 28 is yieldably sustained remote from the rollers 35 by the idler pulley 40 carried by the 65 lever 41 mounted in the fulcrum bracket 42. The short arm of this lever 41 is connected by the linkage 43 to the scale beam 44 in this compound lever weighing system provided with the adjustable weight 45, and the fulcrum 46. The linkage may adjust the scale beam so that its pointer 47 is at the desired 70 position of equilibrium on the graduations 48. The short arm of this scale beam 44 is connected by the link 49 to the anti-frictionally 75 slidable gate 50 automatically reciprocable toward and from the conveyor belt 28 to vary the flow rate of material from the hopper 36 through the opening 51.

This supply way 36 has therein the shaft 80 52 upon which is mounted the vane 53 as a yieldable or movable wall in the supply way directed in the way of material flow and in its suspension movable to restrict the throat or outlet of the upper chute portion of the 85 supply way. This yielding or restricting action is controlled by the weights 54 adjustable by set screws 55 carried by the arms 56 fast with the shaft 52. This compressing action upon the material during its flow is 90 effective, especially with fluffy materials to reduce the flow angle thereof. In instances where the device of this disclosure is used, say in the handling of lime after passing through a pulverizer or mill from burning, 95 there is a substance very freely flowing due to its excessive air content. Adjusting of the squeezing action at the throat by the vane 53 has such a quieting tendency upon this stock to change its state from a freely 100 flowing fluffy stream to a more or less firm or clammy mass, so that its passage on through this supply way of the hopper or chute is readily controlled by the opening 51 for flow out upon the belt 28 upon which belt it 105 will retain the definite contour as provided by the opening 51 and the gate 50.

Between the gate or vane 53 and the gate

50 is disposed the third or controller gate or vane 57, mounted on the shaft 58 provided with the arms 59 carrying the weights 60 as loading means for the vane adjustable thereon by the set screws 61. This vane has its weights 60 so adjusted that in the normal flow of the material, the vane 57 is swung or shifted toward the gate 50 and in the direction of the material flow by such flow of material, as shown in Fig. 6.

Fast on the shaft 58 to be thrown by this vane 57 is the arm 62 having the slot 63 in which is loosely mounted the pin 64 connecting the link 65 as a drag link with the arm 15 66 fast on the shaft 67 extending from the switch box 68. At this position of the parts, as shown in Figs. 3 and 6, there is flow of material and the motor 17 is connected for driving the weighing belt 28 for the maintenance of uniform flow of material from the supply way 36.

Should this flow of material decrease, the weights 60 will swing the vane 57 toward the direction of material flow and the action of 25 the drag link 65 will effect a quick throw of the shaft 67 past its medial or dead point and in this quick throw move the arm 69 having the spring connection 70 with the arm 71 on the shaft 13 to give a snap throw 30 to this shaft 13. This means that if the material supply permits only a gradual swinging back of the vane 57, there is insured through said control means actuatable from the vane a positive and quick throw of 35 the contact carrying disks 12 and 20 by the shaft 13 so that the motor 17 is quickly cut out. This cutting out of the motor 17 throws the contact 72 on the disk 12, Figs. 2 and 4, so that the terminals 73, 74, are 40 closed. The terminal 73 is connected by line 75 with the supply line 3, while this contact 72, in connecting to terminals 74, permits flow through the line 76, coil 77, and line 78' to the supply line 2, thereby completing 45 the circuit through the coil 77 energizing the coil for moving the rockable arm 78 against the resistance of spring 79 so that the arm vibrates to pound the wall of the hopper 36 and loosen any material which 50 may be caught or clinging to the walls of the bin or supply way 36.

If there be no material in this supply way, the vibrator will continue to operate, while the conveyor belt is at rest. However, should 55 there be material which will come down past the vane 53, and act upon the vane 57, this action of the material on the vane 57 will rock the shaft 67 for a quick throw in the opposite direction say from the position 60 shown in Fig. 1 to the position shown in Fig. 6, thus shifting the shaft 67 and its arm 69 to the position shown in Fig. 4, opening the circuit between the lines 75, 76, by moving the contact 72 away from circuit closing 65 position. This will stop the vibrator arm

78 but will simultaneously connect the motor 17 for operating the conveyor belt 28. In some instances, it may be desirable to test out portions of the apparatus, or say operate the vibrator arm 78 manually. This can be effected through the push button switch 80 closing the circuit between the lines 81, 82, connected respectively to the lines 75, 76.

In the event it is desired to start the motor 17 independently of the action of the automatic means herein, the switch 83 may be used to close the circuit from the lines 7, 9, respectively to the lines 16, 22.

This apparatus is one of a simple form, effective for maintaining automatically a uniform flow of material and insuring that such flow of material may not be spasmodic or rush past the gates for disturbing the flow rate, which flow rate is definite and actually determined by the travel of the belt 28.

What is claimed and it is desired to secure by United States Letters Patent is:—

1. A material supply way, and a pair of vanes separately mounted in said way, one 90 of said vanes being provided with means for acting directly on the material in affecting the flow thereof, and the other vane having independent means indirectly acted on by the material for affecting the flow thereof. 95

2. A material supply way, a vane in said way, loading means normally affected by the material flow from said way and first flow changing means for affecting flow to the way, second flow changing means for affecting flow from the way, and mechanism actuatable by the vane for controlling both of said flow changing means. 100

3. A material supply way, a vane in said way, loading means normally affected by the 105 material flow from said way, an endless conveyor for removing material from the way, a motor for actuating the conveyor, and means operable by movement of the vane for controlling the motor to drive the conveyor. 110

4. A material supply way, a vane in said way, leading means normally affected by the material flow from said way, a vibrator above the vane for shaking the material down the supply way to the vane, a conveyor 115 for removing material from the way, a motor for actuating the conveyor, and a switch operable by movement of the vane for stopping the vibrator and starting the motor when the material flow shifts the vane. 120

5. A material supply way including a chute, a suspended vane pivotally mounted in said chute for swinging past a vertical position in the chute, weighted means tending to swing the vane past vertical position toward a side wall in the chute to restrict outlet from said chute, said mounting of the vane being such that on one side of vertical position the weight thrown vane is in position to support material and on the other side of such 125 130

vertical position the vane is thrust upward by the material, an adjusting device for the weighted means, and material flow affecting means actuated by the vane independent of 5 the weighted means adjusted position.

6. A material supply way, a vane in said way, a weight for the vane holding the vane on one side of a vertical position to support material flowing theretoward, a material handling mechanism supplied by 10 material flow from said way, and a control device for the mechanism actuatable by said

vane driven by the material to the other side of said vertical position.

7. A material supply way, a vane in said 15 way positioned by material flow, a vibrator above the vane for agitating the material supplied to said way, and means connected with and actuatable by the vane for actuating the vibrator upon failure of material flow to 20 position the vane.

In witness whereof I affix my signature.

JOHN C. SCHAFFER.
